UNITED STATES PATENT OFFICE.

FREDERICK WILLIAM YOUNG, OF EAST ORANGE, NEW JERSEY.

COMMUTATOR FOR DYNAMO-ELECTRIC MACHINES.

947,768.

Specification of Letters Patent. Patented Jan. 25, 1910.

Application filed July 19, 1909. Serial No. 508,346.

To all whom it may concern:

Be it known that I, FREDERICK WILLIAM YOUNG, a citizen of the United States of America, and a resident of East Orange, 5 county of Essex, and State of New Jersey, have invented certain new and useful Improvements in Commutators for Dynamo-Electric Machines, of which the following is a specification.

10 My invention relates to a commutator in which adjacent to the sides of each bar at which the circuit is broken with the brush, there is placed a zigzag folded metallic strip in contact with the bar which continues in 15 contact with the brush after the bar has left the brush and serves to introduce resistance before the circuit is completely broken between the bar and the brush. The object of the invention is thereby to improve the 20 commutation by reducing the tendency to spark and preventing the commutator bars from burning.

A further object of the invention is to provide this resistance in a structure which is 25 wholly integral with the commutator.

A further object of the invention is to grade the resistance in a series of steps of such value that the current will be reduced in a series of substantially equal steps.

30 In the accompanying sheet of drawings, which forms a part of this application—Figure 1 is a perspective of a portion of a commutator embodying my invention with a composite zigzag folded metallic strip, one 35 of the strips being partly opened. Fig. 2 is a perspective to a smaller scale of one of the composite strips of Fig. 1 before folding, arranged to suitably grade the resistance. Fig. 3 is a perspective of a strip in which the resistance is suitably graded by varying the width at different points along the strip. Fig. 4 is a perspective of a strip which is not graded.

The commutator is composed of the usual 45 copper bars *c c* which are provided with stems *s s* for connection with the coils of the armature in the usual manner. On each side of each bar is a zigzag folded metallic strip *r* for which I find copper of a thick-

ness of five one-thousandths to thirty-five 50 one-thousandths of an inch suitable, but do not confine myself to copper, as high resistance metal such as phosphor bronze or German silver may be substituted. This is folded back and forth on itself in a zigzag, making each section between folds about equal to the length of a commutator bar. The strip is preferably constructed so as to have an increased conductivity near the end which is in 55 contact with the commutator bar so that the current will be cut down in a more uniformly graded manner as the sections of the strip pass out from under the commutator brush. This grading may be effected by thickening the strip at one end, as by laying 60 short strips *t t'* on it as shown in Figs. 1 and 2, or by varying the depth of the strip 65 as shown in Fig. 3. Strips of mica *m m* are laid between the folds of the strip and between adjoining strips in contact with 70 adjoining commutator bars.

As illustrated the folded strip is placed on each side of each bar to provide for both directions of rotation. If it is intended to have the commutator rotate in but one direction it is only necessary that the strip 75 be on the side of each bar which is the last to pass from under the brush.

What I claim as new, and desire to secure by Letters Patent of the United States, is— 80

1. In a commutator, the combination with a commutator bar of a zigzag folded metallic strip in contact with the bar which forms a continuation of the contact surface of the bar and in which the several folds 85 are separated by insulation, substantially as described.

2. In a commutator the combination with a commutator bar of a zigzag folded metallic strip in contact with the bar which forms a continuation of the contact surface of the bar, in which the conductivity of the several folds is decreased from the end in contact with the bar toward the end which is remote from the bar, and in which the several folds are separated by insulation, substantially as described. 95

3. In a commutator, the combination with

a commutator bar of a zigzag folded metallic strip in contact with the bar which forms a continuation of the contact surface of the bar, in which the folds adjacent to the bar 5 have a plurality of layers formed of a plurality of strips in contact, and the number of such layers is diminished toward the end which is remote from the bar, and in which

the several parts are separated by insulation, substantially as described.

10

Signed at East Orange, New Jersey, the 16th day of July, 1909.

FREDERICK WILLIAM YOUNG.
